CLAIM

The ornamental design for a kitchen cutlery handle, as shown and described.

DESCRIPTION

FIG. 1 is a perspective view of a kitchen cutlery handle showing my new design.

FIG. 2 is a right side elevational view thereof.

FIG. 3 is a left side elevational view thereof.

FIG. 4 is an enlarged front elevational view thereof.

FIG. 5 is an enlarged rear elevational view thereof.

FIG. 6 is a top plan view thereof; and,

FIG. 7 is a bottom plan view thereof.

The broken lines for the cutlery blade and logo on the handle in FIGS. 1–7 represent environmental subject matter and form no part of the claimed design.

1 Claim, 4 Drawing Sheets# US D809,864 S
